FASTENING INSERTING MACHINE

William Thomas Buckingham Roberts, Leicester,
England, assignor to United Shoe Machinery
Corporation, Flemington, N. J., a corporation of
New Jersey

Application May 16, 1944, Serial No. 535,808
In Great Britain May 19, 1943

8 Claims. (Cl. 1—18.1)

This invention relates to machines having means for inserting fastenings, and is herein illustrated as applied to a power-operated toe-lasting machine of that character constructed generally as disclosed in United States Letters Patent No. 2,134,148, granted on October 25, 1938, on an application of mine. It is to be understood, however, that the invention is not thus limited in its applicability.

The machine shown in the above-mentioned Letters Patent is provided with wipers which wipe the toe end of the upper heightwise of the last and are thereafter moved lengthwise and widthwise of the last to wipe the margin of the upper inwardly over an insole on the last, and with a group of tackers which drive tacks in locations a little farther inwardly over the shoe bottom than the wiping edges of the wipers to fasten the margin of the upper to the insole. These tackers are engaged and controlled by plates which are moved lengthwise and widthwise of the last in paths similar to the paths of movement of the wipers to impart corresponding movements to the tackers from initial retracted positions, and the tackers are also moved heightwise of the last into contact with the margin of the upper beyond the edges of the wipers prior to the tack-driving operation. The several tackers comprise nozzle members having therein driver passages in which drivers are movable to drive the tacks and having also other passages through which the tacks are fed into the driver passages from suitable tack-separating means.

While such machines have been used with highly satisfactory results, it sometimes happens, especially in operating on men's shoes having very thick, heavy uppers, that a machine fails to drive the full number of tacks. Such a shoe may have a toe stiffener of the kind which is softened by a solvent prior to the toe-lasting operation, and it may be provided also with an extra toe cap of thick leather which it is customary to wet thoroughly with water prior to lasting. When the toe wipers wipe the margin of the upper inwardly over the insole under those conditions, some of the liquid may ooze from the upper and mix with dust on the shoe, forming more or less viscous matter some of which may adhere to the ends of the tack drivers and be carried up into the driver passages when the drivers are retracted. An accumulation of such foreign matter at the junction of some driver passage and the corresponding tack-feeding passage may eventually interfere with the feeding of tacks into the driver passage.

An object of the present invention is to avoid any failure in the feeding of tacks resulting, for example, from conditions such as above described. To this end, the machine herein shown is provided with automatic means for shaking the tackers to dislodge any tack which may have been caught at the entrance to a driver passage and also, it may be, to dislodge any foreign matter interfering with the feeding of tacks. More particularly, the construction shown comprises continuously reciprocating means which serves thus to shake the tackers only when they are in their initial retracted positions by movements imparted to the above-mentioned tacker-controlling plates.

The invention will now be more particularly described with reference to the accompanying drawings showing an illustrative embodiment thereof and will thereafter be pointed out in the claims.

20 In the drawings, Fig. 1 is a view in right-hand side elevation of a portion of the machine in which the invention is shown as embodied;

25 Fig. 1a is a view similar to Fig. 1 of a portion of the structure, but with some of the parts in different positions;

Fig. 2 is a view in rear elevation of a portion of the structure shown in Fig. 1 and of other parts not therein shown;

30 Fig. 3 is mainly a plan view showing the tacker-controlling plates and parts closely associated therewith;

Fig. 4 is mainly a vertical sectional view showing the toe end of a shoe and parts adjacent thereto prior to the operation of the wipers on the upper;

35 Fig. 5 is a view similar to Fig. 4, but showing the parts as they appear at the time of the tack-driving operation;

40 Fig. 6 is mainly a plan view showing the wipers and the tackers as they appear in relation to the shoe at the same time in the operation of the machine as in Fig. 5; and

Fig. 7 is mainly a vertical sectional view showing 45 one of the tackers and associated parts with the tack driver as it appears at the end of its tack-driving movement.

In accordance generally with disclosure of the previously mentioned Letters Patent, the shoe is 50 positioned bottom upward for the toe-lasting operation with its forepart clamped between a holdown 2 and a toe rest 4 (Fig. 4) and with its heel end engaged by a heel rest (not herein shown) which assists in holding it against 55 lengthwise displacement. The means for thus

positioning and holding the shoe may embody features further disclosed in United States Letters Patent No. 2,135,677, granted on November 8, 1938, on an application of mine. For lasting the toe end of the shoe there are provided wipers 6 (Figs. 4, 5 and 6) which first wipe the upper heightwise of the last and are thereafter advanced bodily lengthwise of the shoe and closed inwardly over the shoe bottom by movements laterally of the shoe about a vertical axis to wipe the margin of the upper over the insole. Associated with the wipers are members 8 which spread the margin of the upper from over the insole and by clamping it on the wipers serve as retarders to insure that the upper will be wiped tightly and smoothly over the last and the insole. After thus operating on the upper these members are retracted lengthwise of the shoe and are moved downwardly to the positions in which they are shown in Fig. 5. After their first inward wiping movements the wipers are preferably retracted nearly but not quite to the edge of the insole and are then moved inwardly again to positions where their wiping edges are not so far from the edge of the insole as at the end of their first inward movements, ready for the driving of tacks to fasten the upper to the insole, as further disclosed in United States Letters Patent No. 2,140,652, granted on December 20, 1938, on an application of mine.

For fastening the margin of the upper to the insole there is provided a group of tackers 10 arranged to drive a gang of tacks simultaneously around the toe end of the shoe bottom in locations just beyond the inner edges of the wipers. These tackers are initially positioned considerably higher than the shoe, as shown in Fig. 4, to avoid interference with the retarder members 8. Each of the several tackers is constructed as shown in Fig. 7. It comprises an arm 12 suspended at its upper end on a flange member 14 which has a horizontal curvature generally similar to that of the edge of the toe end of the shoe bottom and is secured to a vertically movable supporting member 16. By reason of the manner in which the arm 12 is thus supported it may be swung inwardly and outwardly in directions transverse to the edge of the shoe bottom. At its lower end the arm 12 carries a nozzle member 18 having therein a driver passage 20 in which is movable a tack driver 22, this driver being shown in Fig. 7 as at the end of its tack-driving movement. Also formed in the nozzle member 18 is a passage 24 through which tacks are fed into the driver passage 20, the tacks being delivered through a flexible tube 26 from tack-separating means (not shown). Each tack is supported in the driver passage 20 by a leaf spring 28 which extends into the passage when the driver is retracted and is displaced by the downward movement of the driver. The driver 22 is secured to a driver bar 30 which is movable downwardly and upwardly along the arm 12 and is provided with a recess to receive the outer edge portion of a downwardly and upwardly movable driver-operating member 32. This construction permits the several arms 12 to be swung inwardly and outwardly as above described while maintaining an operative relation between the driver bars 30 and the member 32. The member 16, which corresponds to the member 247 shown in Letters Patent No. 2,134,148, is moved downwardly at the proper time to position the tackers heightwise in proper relation to the shoe bottom by mechanism including a lever 34 (Fig. 1), as

fully disclosed in said Letters Patent. The member 32, which corresponds to the member 268 shown in the last-mentioned Letters Patent, also is moved downwardly at the proper time to operate the tack drivers by spring means (not shown) controlled by mechanism including a lever 36, as also fully disclosed in said Letters Patent.

The positions of the several tackers 10 with respect to inward and outward swinging movements are determined by tacker-controlling plates 38 which are moved lengthwise and widthwise of the shoe in paths similar to the paths of movement of the wipers. These plates correspond generally to the plates 293 shown in Letters Patent No. 2,134,148, but in the construction herein shown the nozzle members 18 of the tackers, instead of being positioned in slots in the plates, are engaged by the inner edges of the plates (Fig. 3) which are curved similarly to the wiping edges of the wipers. The nozzle members are held against these edges by springs 40 connected to the arms 12 and tending to swing the arms outwardly, one of these springs being shown in Fig. 7. The plates 38 are advanced bodily lengthwise of the shoe and are swung or closed inwardly widthwise of the shoe in time relation to corresponding movements of the wipers to cause the tackers to be properly grouped and positioned relatively to the edges of the wipers when the tacks are driven, the tackers being moved downward to carry their nozzle members 18 into engagement with the overwiped margin of the upper just beyond the inner edges of the wipers, as illustrated in Figs. 5 and 6. The tacker-controlling plates 38 are detachably supported on carrier plates 42 (Fig. 3) which are mounted on a table 44 (see also Fig. 1) suspended on the lower ends of a plurality of links 46 corresponding to the links 291 shown in Letters Patent No. 2,134,148. These links by swinging movements permit the table 44 and the tacker-controlling plates 38 thereon to be advanced and retracted lengthwise of the shoe, and through means controlling the links the table is moved downwardly and upwardly with the tackers, so that the plates 38 are positioned at all times heightwise in the same relation to the tacker nozzles, as fully disclosed in Letters Patent No. 2,134,148. The carrier plates 42 are provided with cam slots 48 in which lie rolls 50 supported on the table 44 to guide the carrier plates and their tacker-controlling plates 38 in their closing and opening movements. Connected to the carrier plates are links 52 and connected to the table 44 are links 54, the links 52 and 54 corresponding respectively to the links 293 and 291 shown in the last-mentioned Letters Patent. It will be understood that through these links the advancing and closing movements are imparted to the tacker-controlling plates 38 in proper time relation to the movements of the wipers. Each of the links 54 through which movements are imparted to the table 44 is pivotally connected at its rear end to a sleeve 56 which is movable forwardly and rearwardly along a guide member 58, as illustrated in Fig. 1, and each sleeve 56 is connected by a link 60 to the lower end portion of a lever 62 pivotally mounted at its upper end. It will be understood that there are two of these levers associated respectively with the two link connections to the table 44, these levers corresponding to the levers 296 shown in Letters Patent No. 2,134,148 and being operated by the means therein fully disclosed,

As hereinbefore explained, under some conditions viscous matter on the bottom of the shoe may adhere to the lower ends of the tack drivers 22 and be carried upwardly into the driver passages 20 when the drivers are retracted after driving the tacks. In order to prevent any accumulation of such foreign matter at the junction of any driver passage and the corresponding tack-feeding passage 24 from interfering with the proper feeding of tacks into the driver passage, the present invention, in its illustrative embodiment, provides means for imparting rapid reciprocatory movements in directions lengthwise of the shoe to the table 44 which supports the tacker-controlling plates 28 to shake the tackers when they are in their initial retracted positions. To permit such movements of the table, pin-and-slot connections are provided between the links 60 and the levers 62, each of such connections comprising a pin 64 extending from the lever into a slot 66 in the link. Each of the links 60, moreover, has a rearward extension 68 arranged to be engaged on its rear end by a finger 70 formed on a collar 72 which is fast on a rockshaft 74 corresponding in location to the rod 307 shown in Letters Patent No. 2,134,148. Also fast on the rockshaft 74 is a downwardly and rearwardly extending arm 76 the lower end of which is forked to embrace a block 78 supported on a pin 80 (Fig. 2) which is eccentrically mounted on one end of a shaft 82 supported in a bracket 84 on the rear of the machine. One the other end of the shaft 82 is secured a friction disk 86 the periphery of which is engaged by the inner surface of a pulley 88 through which the machine is operated, this pulley being driven continuously by a belt (not shown) from a suitable source of power. The shaft 82 may be driven, for example, at a speed of about 900 revolutions a minute, and accordingly the oscillating fingers 70, acting on the rear ends of the links 60, impart rapidly repeated forward movements to the table 44, the return movements of the table being effected by springs 90 connected to the sleeves 56. Such movements are imparted to the table only when the tackers are in their initial retracted positions, since the levers 62, in imparting advancing movement to the table in time relation to the corresponding movement of the wipers early in the cycle of operations of the machine, withdraw the rearward extensions 68 of the links 60 from the paths of oscillatory movement of the fingers 70, as illustrated in Fig. 1a. It will be understood, moreover, that when the table is retracted in response to return movements of the levers 62 later in the cycle, after the driving of the tacks, the rearward extensions of the links are again carried into the paths of movement of the fingers, as illustrated in Fig. 1, to cause the desired shaking of the tackers. Substantial insurance is thus afforded that any tack which by reason of the presence in a tacker of foreign matter such as hereinbefore described, or for some other reason, may have been caught and have failed to enter the driver passage will be dislodged to cause it to enter the passage. It is contemplated also that the shaking of the tackers will assist in dislodging therefrom any foreign matter which may be present therein.

While the invention is herein illustratively disclosed as applied to a machine which drives tacks, it will be understood that the invention is not limited to machines which drive fastenings of that particular character.

Having described the invention, what I claim as

new and desire to secure by Letters Patent of the United States is:

1. In a machine for lasting the margin of an upper around an end of a shoe inwardly over the shoe bottom, a group of fastening-inserting devices arranged to insert fastenings around the end of the shoe bottom to fasten the upper in lasted position, said fastening-inserting devices having driver passages and drivers movable therein and having also other passages from which fastenings are fed into the driver passages, and automatic means for shaking said fastening-inserting devices to assist in avoiding failure of any fastenings to enter the driver passages.
2. In a machine for lasting the margin of an upper around an end of a shoe inwardly over the shoe bottom, a group of fastening-inserting devices arranged to insert fastenings around the end of the shoe bottom to fasten the upper in lasted position, said fastening-inserting devices having driver passages and drivers movable therein and having also other passages from which fastenings are fed into the driver passages, said devices being movable from initial positions into fastening-inserting positions, and automatic means for continuously shaking said devices when they are in their initial positions to assist in avoiding failure of any fastenings to enter the driver passages.
3. In a machine for lasting the margin of an upper around an end of a shoe inwardly over the shoe bottom, a group of fastening-inserting devices arranged to insert fastenings around the end of the shoe bottom to fasten the upper in lasted position, said fastening-inserting devices having driver passages and drivers movable therein and having also other passages from which fastenings are fed into the driver passages, said devices being movable from initial positions into fastening-inserting positions, and power-driven means into operative relation to which said devices are movable in returning to their initial positions for shaking them to assist in avoiding failure of any fastenings to enter the driver passages.
4. In a machine for lasting the margin of an upper around an end of a shoe inwardly over the shoe bottom, a group of fastening-inserting devices arranged to insert fastenings around the end of the shoe bottom to fasten the upper in lasted position, said fastening-inserting devices having driver passages and drivers movable therein and having also other passages from which fastenings are fed into the driver passages, means for moving said devices lengthwise of the shoe toward fastening-inserting positions and for thereafter retracting them, and continuously reciprocating means into operative relation to which said devices are movable when they are thus retracted for shaking them to assist in avoiding failure of any fastenings to enter the driver passages.
5. In a lasting machine having wipers movable lengthwise and laterally of a shoe to wipe the margin of the upper around an end of the shoe inwardly over the shoe bottom into lasted position, a group of fastening-inserting devices arranged to insert fastenings around the end of the shoe bottom to fasten the upper in lasted position, said fastening-inserting devices having driver passages and drivers movable therein and having also other passages from which fastenings are fed into the driver passages, members movable in paths similar to the paths of the

wipers for controlling said fastening-inserting devices and for positioning them relatively to the wipers prior to the insertion of the fastenings, and automatic means arranged to act through said members to shake said devices and thereby to assist in avoiding failure of any fastenings to enter the driver passages.

6. In a lasting machine having wipers movable lengthwise and laterally of a shoe to wipe the margin of the upper around an end of the shoe inwardly over the shoe bottom into lasted position, a group of fastening-inserting devices arranged to insert fastenings around the end of the shoe bottom to fasten the upper in lasted position, said fastening-inserting devices having driver passages and drivers movable therein and having also other passages from which fastenings are fed into the driver passages, members movable in paths similar to the paths of the wipers for controlling said fastening-inserting devices and for positioning them relatively to the wipers prior to the insertion of the fastenings, means for thus moving said members and for thereafter retracting them, and power-driven means arranged to act through said members when they are in their retracted positions to shake said devices and thereby to assist in avoiding failure of any fastenings to enter the driver passages.

7. In a lasting machine having wipers movable lengthwise and laterally of a shoe to wipe the margin of the upper around an end of the shoe inwardly over the shoe bottom into lasted position, a group of fastening-inserting devices arranged to insert fastenings around the end of the shoe bottom to fasten the upper in lasted position, said fastening-inserting devices having driver passages and drivers movable therein and having also other passages from which fastenings

are fed into the driver passages, members movable in paths similar to the paths of the wipers for controlling said fastening-inserting devices and for positioning them relatively to the wipers prior to the insertion of the fastenings, mechanism movable to operate said members and reversely movable to retract them, and continuously reciprocating means into operative relation to which said mechanism is thus reversely movable for shaking said fastening-inserting devices to assist in avoiding failure of any fastenings to enter the driver passages.

8. In a lasting machine having wipers movable lengthwise and laterally of a shoe to wipe the margin of the upper around an end of the shoe inwardly over the shoe bottom into lasted position, a group of fastening-inserting devices arranged to insert fastenings around the end of the shoe bottom to fasten the upper in lasted position, said fastening-inserting devices having driver passages and drivers movable therein and having also other passages from which fastenings are fed into the driver passages, members movable in paths similar to the paths of the wipers for controlling said fastening-inserting devices and for positioning them relatively to the wipers prior to the insertion of the fastenings, mechanism including links connected to said members for advancing them lengthwise of the shoe and for thereafter retracting them, and reciprocating means arranged to act through said links only when the members are in their retracted positions to shake said fastening-inserting devices and thereby to assist in avoiding failure of any fastenings to enter the driver passages.

WILLIAM THOMAS BUCKINGHAM
ROBERTS.
